UNITED STATES PATENT OFFICE.

JOSEPH H. LA ROUCHE, OF LYNN, MASSACHUSETTS, ASSIGNEE, BY MESNE ASSIGNMENTS, TO UNITED SHOE MACHINERY CORPORATION, OF PATERSON, NEW JERSEY, A CORPORATION OF NEW JERSEY.

APRON FOR SHOE-SEWING MACHINES.

1,269,097.

Specification of Letters Patent. Patented June 11, 1918.

Application filed August 30, 1916. Serial No. 117,765.

To all whom it may concern:

Be it known that I, JOSEPH H. LA ROUCHE, a citizen of the United States, residing at Lynn, in the county of Essex 5 and State of Massachusetts, have invented certain new and useful Improvements in Aprons for Shoe-Sewing Machines; and I do hereby declare the following to be a full, clear, and exact description of the invention, 10 such as will enable others skilled in the art to which it appertains to make and use the same.

The present invention relates to an improvement in aprons for shoe sewing machines of the curved needle, lock stitch type 15 such as are used for stitching the outer soles to the welts.

Shoe sewing machines of this type are commonly provided with a guard or apron 20 located at the front of the machine and below the work table to prevent the looper and its associated parts from marring or otherwise disfiguring the shoe upper during the sole stitching operation. These aprons have 25 been arranged in various ways. The most usual arrangement is to removably secure the apron at its lower end to the machine so as to permit of ready access to the parts covered by the apron, leaving the upper 30 end of the apron free, or resting against the work table or a fixed part of the machine. Both these upper end arrangements are undesirable, the former because not only may the apron be pushed against the looper as 35 the shoe is fed during the stitching operation, but also because the apron may be pushed inwardly far enough for the needle to strike it, and if the apron is of metal, to be thereby damaged; and the latter because 40 when the apron rests against the work table and there is sufficient clearance between the looper and the apron for some adjustments of the looper, there is not sufficient clearance between them for other adjustments of the 45 looper, and consequently the looper strikes the apron as it loops the thread around the needle. The arrangement by which the upper end of the apron rests against the work table is open to the further objection that 50 the apron is thereby so positioned that it is liable to interfere with the proper manipulation of the shoe.

The object of the present invention is to

provide an apron and support for the above described type of shoe sewing machine, having provision whereby the apron may be adjusted correspondingly to the adjustments of the looper so that the distance of its upper part, which is in close proximity to the looper, may be unchanged with relation 55 thereto, the lower end of the apron remaining in unadjusted or fixed position. By means of this arrangement, not only is the apron in proper relation to the looper so as not to be struck thereby, but also, and as a 60 consequence thereof, the apron is prevented from being struck by the needle. This object is accomplished by the invention hereinafter described and particularly pointed 65 out in the claims.

In the accompanying drawings illustrating the preferred form of the invention, Figure 1 is a side elevation of so much of a lock stitch shoe sewing machine as is necessary to show the application of the improved apron and supporting means thereto; Fig. 2 is a front elevation of the parts shown in Fig. 1; and Fig. 3 is a detail view in perspective of the adjustable abutment block against which the upper end of the 70 apron (shown in dot and dash lines) is adapted to rest.

The parts of the lock stitch shoe sewing machine illustrated in the drawings comprise a curved hook needle 4, a curved awl 6, a presser 85 foot 8, an edge gage 10, a work supporting table 12, a thread finger 14, a looper 16, and a flanged plate 18, together with other stitch forming elements. The arrangement and mode of operation of these stitch forming 90 devices are described with substantial accuracy in United States Letters Patent No. 1,169,909. The improved apron 22 is located at the front of the machine just below the work table, and consists of a thin sheet of 95 resilient metal removably secured at its lower end to a bracket 24 fastened in like manner to the upper front side of the plate 18. The upper end of the apron is freely supported. By means of this construction the apron may 100 be swung to one side to afford access to the looper or other parts covered by the apron. The upper end of the apron terminates immediately below the work table and is provided with a shoulder 26 which is adapted to engage 105 a stop boss 28 extending forwardly from an

adjustable abutment block 30, against which the operator presses the apron as he guides the shoe. The relation of the shoe to the work table and apron while the outer sole is being 5 stitched to the welt is illustrated in Fig. 1. The shoe is fed from right to left (viewing Fig. 2) during the stitching operation and the operator presses the shoe inwardly so that the shoe upper, a portion of which is 10 represented at 34, rubs against the upper portion of the apron. The drag of the shoe upper against the apron causes the shoulder 26 to be forced against the stop boss 28, which thereby prevents the apron from 15 swinging to the left out of operative position.

The adjustable abutment block may be secured to any convenient part of the machine, and in the present form of the invention it is secured to the under side of 20 the work table, being fastened thereto by the same screw 36 by which the work table is secured to the machine. The abutment block is provided with a slot 38 formed longitudinally 25 of its length, by which it may be adjusted inwardly or outwardly according to the path of travel of the looper, in order that the looper may not strike the apron during the looping operation. Extending downwardly from the front end of the abutment block is a flange 40 which affords a bearing 30 surface against which the apron is pressed and by which it is prevented from touching the looper. It will be observed that the upper 35 end of the apron is held against the abutment block by its own resiliency. The adjustability of the abutment block compensates for the various adjustments of the looper; and when it is secured in adjusted 40 position relatively to the looper, the abutment block affords a positive support for the apron so that it may not be pushed into the path of the needle and cause injury to the needle.

45 By means of the structure of the present invention the upper end of the apron may be adjusted relatively to the looper, to the edge gage, and to the other stitch forming

parts, while the lower end of the apron remains in fixed position. 50

Having thus described the invention, what is claimed is:—

1. A lock stitch shoe sewing machine having, in combination, stitch forming devices including a curved hook needle, a looper, a 55 work table, an apron interposed between the looper and the shoe operated upon, and means for supporting the upper end of the apron having provision whereby the upper end only of the apron may be adjusted relatively to the looper and work table. 60

2. A lock stitch shoe sewing machine having, in combination, stitch forming devices including a curved hook needle, a looper, a work table, an apron secured at its lower end 65 to the machine, and an abutment against which the upper end of the apron is adapted to rest having provision whereby the position of the upper end of the apron may be adjusted relatively to the looper independently of the lower end of the apron. 70

3. A lock stitch shoe sewing machine having, in combination, stitch forming devices including a curved hook needle, a looper, a work table, an apron having a shoulder at 75 its upper end, and an adjustable abutment provided with a boss with which the shoulder is adapted to engage during the stitch forming operation.

4. A lock stitch shoe sewing machine having, in combination, stitch forming devices including a curved hook needle, a looper, a work table, an apron interposed between the looper and the shoe operated upon removably secured at its lower end to the machine, and 85 an adjustable abutment mounted on the work table for supporting the upper end of the apron. 90

5. A lock stitch shoe sewing machine having, in combination, stitch forming devices including a curved hook needle, a looper, a work table, an edge gage, an apron, and means for supporting the upper end of the apron and for adjusting it relatively to the looper and to the edge gage. 95

JOSEPH H. LA ROUCHE.
